UNITED STATES PATENT OFFICE.

DANIEL B. YOUNGBLOOD, OF CHARLOTTE, MICHIGAN.

HOISTING-BUCKET.

1,128,397.

Specification of Letters Patent. Patented Feb. 16, 1915.

Application filed March 6, 1913. Serial No. 752,519.

To all whom it may concern:

Be it known that I, DANIEL B. YOUNGBLOOD, citizen of the United States, residing at Charlotte, in the county of Eaton and State of Michigan, have invented certain new and useful Improvements in Hoisting-Buckets, of which the following is a specification.

This invention relates to an improvement in hoisting buckets.

The primary object of the invention is to provide a bucket which is supported by a hoisting mechanism, which may be used to load coal or other material from cars or bunkers into vehicles.

A further object of the invention is to provide a bucket of this character in which the dumping of the load may be accomplished in a convenient manner, the bucket assuming a closed position as soon as the load has been dumped.

Another object of the invention is to provide simple means for normally supporting the door sections which constitute the dumping bottom against movement, said mechanism acting in conjunction with resilient means which closes the door sections as soon as the load has been deposited.

For a full understanding of the invention, reference is to be had to the following description and accompanying drawings, in which:

Figure 1 is a front elevation; Fig. 2 is an end elevation; Fig. 3 is a longitudinal section, the door sections being shown in their open position; Fig. 4 is a sectional view showing the arrangement of the latch mechanism; Fig. 5 is a detail view of one of the latch releasing members.

Corresponding and like parts are referred to in the following description and indicated in all the views of the drawings by the same reference characters.

In the drawings, 10 designates a receptacle which is preferably rectangular, consisting of side walls 11 and end walls 12. While this receptacle has been illustrated as constructed of sheet metal, it will be noted that the same may be formed of wood properly reinforced, or any other suitable material, the mechanism which forms the subject-matter of the present invention in no way depending upon the specific construction of the receptacle.

The terminals 13 of a yoke or handle member 14 are secured to the end walls 12.

This handle member supports a sheave block 15 over which the hoisting cable 16 passes. By this construction, it will be noted that the bucket may be handled by any suitable hoisting and conveying mechanism.

A plurality of supporting plates 17 are secured to the inner face of the side walls 12 adjacent their lower edges. These plates each hingedly support a door 18, the edges 19 of the doors abutting when they are closed, the doors thereby forming the bottom of the bucket. An angle iron 20 is secured to the face of each of the doors adjacent its free edge, these angle bars reinforcing the doors and forming engaging surfaces for the latch mechanism which will be hereinafter described. Each of the doors is normally maintained closed by a plurality of coiled springs 23, the coiled springs 75 being secured at one end to the upper edge 24 of the bucket, their lower terminals 25 being secured to the doors 18. It will be noted by this construction that these springs will maintain the doors closed when the bucket is unloaded, but that the load will actuate the doors against the tension of the coiled springs.

The extensions 13 of the handle 14 are continued to a point adjacent the center 85 of the bucket. A latch member 26 is secured to each of these extensions, said latch members being formed of relatively heavy resilient material. The terminal 27 of the latch member is enlarged and disposed at 90 right angles to the body portion of the member, said terminal engaging the portions 28 of the angle bars which are carried by the doors, securely holding the doors against opening when the bucket is loaded.

A latch releasing member is pivotally supported on each end of the bucket, and consists of a lever 29, the terminal 30 of which is provided with a foot 31. This foot is provided with a cam face 32 which, when the lever 29 is actuated, will force the lower terminal of the member 26 away from the bucket. A stop 33 is arranged on the end of the bucket in the path of the lever 29, the lever normally being maintained in contact with this stop by the coiled spring 34, one terminal of which is connected to the lever and the other to the bucket. Thus, it will be obvious that the terminal 31 of the lever 29 will be normally maintained out 110 of contact with the latch member 26.

A cable 35 is connected to the upper ter-

5 minal of the lever 29, said cable passing over a sheave 36 supported in a bracket 37 which is arranged on the handle 14. It will be understood that the latch mechanisms are duplicated on both sides of the bucket, and the cables 35 are passed over sheaves 38 supported by the block 15. A cable 39 is connected to the cable 35, this cable being drawn when it is desired to release the doors. When the bucket has been filled with material and conveyed to the point where it is to be dumped, the operator pulls the cable 39 which through the cables 35 will swing the lever 29 on its 10 pivot against the tension of the coiled spring 34. The cam face 32 of the extension 31 of the lever contacts with the resilient latch member 26, and as the pull on the cable is continued the extension 37 of the latch member will be forced out of contact with the portions 28 of the angle bars 20. As soon as the latch members 26 on both 15 sides of the bucket are thus released, the weight of the load will open the doors against the tension of the coiled springs 23. When the load has been deposited, and there is no longer pressure on the doors, the springs 23 will draw in the doors to their closed position, the angle bars 20 being received by the latch members 26. It will be seen that the springs 34 will return the lever 29 to a position where it will not contact with the latch members 26 as soon as the pull on the cable 39 is released.

20 5 The many advantages of a construction of this character will be clearly apparent, as it will be noted that the device provides an efficient conveying receptacle, which may be conveniently dumped, and in which the door sections constituting the closure, are returned to their closed position as soon as the load is deposited. It will also be seen that the structure may be easily and economically manufactured, and that the various parts may be readily assembled.

45 Having thus described my invention, what I claim as new and desire to secure by Letters Patent is:—

1. In a latch mechanism for containers having a body member and a hinged door forming the bottom thereof, a resilient keeper member carried by the body member, a terminal extension formed on the keeper

and adapted to normally engage against the bottom face of the door, and a releasing means for the keeper, said means including a lever pivoted to the body member, and a cam face foot carried by the lever and adapted to be moved thereby to position between the keeper and the body member for spacing the keeper therefrom and withdrawing the extension from engagement with the door.

2. A latch mechanism for containers having a body member and a hinged door forming the bottom thereof, said latch mechanism including means for locking the door in closed position and means for releasing the door, said first-mentioned means including a resilient keeper carried by the body member, and a terminal extension formed on the keeper and adapted to normally engage against the bottom face of the door, said releasing means including a lever pivoted to the body member, and a wedge-shaped foot member carried by the lever, the inclined face of the foot lever being adapted to serve as a cam for spacing the foot from the body member when moved to position between the keeper and the body member, said extension being withdrawn from engagement with the door when the keeper is spaced from the body member.

3. A latch mechanism for containers having a body member and a pair of hinged doors forming the bottom thereof, said mechanism including a resilient keeper member secured to the body member, a terminal extension formed in the keeper and arranged to normally engage the adjacent terminals of the doors against the bottom faces thereof for holding the doors in closed position, and means for withdrawing the extension from engagement with the doors, said means including a lever pivoted to the body member and a wedge-shaped foot carried by the lever and movable to position between the keeper and the body member for withdrawing the extension from engagement with the doors.

In testimony whereof I affix my signature in presence of two witnesses.

DANIEL B. YOUNGBLOOD.
